UNITED STATES PATENT OFFICE.

HENRY ALEXANDER TURNBULL, OF SURREY HILLS, VICTORIA, AUSTRALIA.

WATER-TUBE BOILER.

1,229,171.

Specification of Letters Patent. Patented June 5, 1917.

Application filed July 22, 1915. Serial No. 41,221.

To all whom it may concern:

Be it known that I, HENRY ALEXANDER TURNBULL, residing at 50 Newton street, Surrey Hills, in the State of Victoria and Commonwealth of Australia, a subject of the King of Great Britain, have invented certain new and useful Improvements in Water-Tube Boilers, of which the following is a specification.

10 This invention is devised to secure greater efficiency in the production of and maintenance of a steam supply for marine and other engines, and for all other purposes. One of the characteristics and objects of the

15 combination of parts as hereinafter described is the provision of a set of steam generating "elements" which shall be separately removable and interchangeable and at the same time adapted to produce the

20 most rapid circulation and a high pressure of steam with economy of fuel. Another object is to attain the before stated result with the minimum of expenditure for cleaning and repairs and to enable the same to

25 be conducted with little inconvenience and without long stoppage of the engines or work.

One of the principal features of my invention is that the boiler consists of a number of sets of straight vertical water tubes or steam generating tubes. A number of these are joined at the top to a header tube, which is horizontal, all being of convenient length and diameter to suit the various requirements and purposes. A similar header is provided at the bottom. The two headers and set of vertical tubes constitute one of the elements referred to. The connection of the top and bottom header by the vertical tubes in the manner described allows tubes of smaller size to be used, and obtains greater effective circulation of water through the tubes, than previously practicable on a given basis. The number of tubes and the length and size are adjusted to suit requirements. Any required number of such elements are placed within the furnace combustion space side by side. All the bottom headers are connected with a mud drum and the top headers with a steam water drum. Each bottom header and top header with the set of vertical tubes forms an element which element is interchangeable with other elements thus greatly facilitating cleaning and repairs.

One embodiment of my invention and

some modification to suit differing conditions are illustrated in the accompanying drawings in which—

Figure 1 is a side sectional elevation of 60 boiler with transverse steam and water drum.

Fig. 2 is an end sectional elevation of 65 boiler taken through line X—X Fig. 1 and looking in the direction of arrow X.

Fig. 3 is a back view of Fig. 1 looking in the direction of arrow Y.

Fig. 4 is a side sectional elevation of 70 boiler with longitudinal steam and water drum.

Fig. 5 is an enlarged section through 75 downtake mud drum and lower header.

Fig. 6 is an alternative method of hand 80 hole fitting at front end of headers.

Fig. 7 is an enlarged section of mud drum 85 showing an alternative method of fixing lower header in same.

Fig. 8 is an elevation of mud drum and 90 with lower header as shown in Fig. 5 fitted to same.

Fig. 9 is an arrangement of tubes and cast 95 iron spreaders for supporting baffles.

Fig. 10 is an elevation of tubes showing 100 baffles.

Fig. 11 is a view showing a valve and 105 fitting to a down pipe.

One of the most useful ordinary embodiments of my invention is illustrated in Figs. 1, 2 and 3. The part marked 2 is the furnace, 4 the furnace bar, 6 the furnace door opening, and 8 is part of the fire brick lining. 10 is the bottom header and 12 the top header, 13 the vertical tubes, 14 the mud drum, 15 the water and steam drum, 16 down comer, 17 man hole door, and 18 the steam off take. 19 shows the jointing of the upper end of the down comer. The end is expanded into the bottom of the steam and water drum, strengthening plate 20 being fitted inside the shell plate 21. The element will be seen in Fig. 1 consisting of bottom header 10, top header 12, and set of vertical tubes 13, which are fifteen in this case, but may be any number more or less. The joint between the upper header and the water drum may be formed in one or other of the ways shown in Figs. 5 or 7. Both or either of these may be applied to top or bottom headers. The vertical tubes may be fitted to the top header by expanding and 110 the bottom header by screwing or if desired both top and bottom ends may be expanded

into the top and bottom headers respectively. Each down comer is joined to the mud drum by a joint as shown. 22 are the screw plugs at the top of each tube 13. 23 is the uptake, 24 is the steel casing of boiler, which may have suitable doors or openings as at 47 for inspection and cleaning purposes. The boiler is sometimes portable being inclosed entirely by metal casing or it may be 10 totally inclosed by brick work or partly of one and partly of the other.

Fig. 2 is a sectional elevation showing the same parts and also gage glass 25 and diagrammatically superheater 26 (Fig. 1).

15 Fig. 3 illustrates an end sectional elevation of the boiler.

In the bottom of the mud drum opposite to the bottom of each down comer is a hand hole 27 fitted with a hand hole door 28. 20 Opposite horizontally to the end of each bottom header is fitted a similar hole and cover 31, closing the ends of mud drum. At the front end of each top and bottom header is fitted a removable screw cap 29 or a hand hole door 30 both as shown in detail in Figs. 5 and 6 respectively. The mud drum is shown square but both it and the headers may be of square, round or oval section.

Each down comer may be, though it is not 30 always necessary, fitted at its top end with a valve such as a miter valve seating upon the annular top of the down comer. The valve is attached to a stem extending upwardly through a screw passage in the top of the drum and being at the top attached to a wheel exterior of the drum by turning which the valve passage is opened and closed. Any other approved valve such as the screw down or gate type may be adopted 35 if preferred to the foregoing. Such valve is illustrated in Fig. 11. 16 is the down comer which in this case is shown attached to the shell 21 of the steam water drum by means of a flange 52. The down comer extends upwardly to within the steam water drum 15 and is formed with a miter seat 53 upon which seats the valve 54 which has a stem 55 extending to a wheel handle 56 external to the drum. A suitable packed gland connection 57 is to keep the valve stem 40 steam tight.

The elements are sometimes placed one a little forward of the other so that the position of the vertical pipes is staggered as 45 shown in Fig. 9, in order to better attain the advantage of the products of combustion.

In the steam water drum for the purpose of more effectively separating the water from the steam as it emerges from the top header 60 a small baffle plate 49 (Fig. 1) may be provided opposite the opening where the steam emerges.

The water level in the steam water drum is arranged to be at a desired predetermined 65 position either above or below the entrance

from the header. A perforated dry pipe 48 or a steam dome may be attached. The economizer referred to may be at any suitable position in the upper part of the furnace chamber or elsewhere (one example 70 being shown in Fig. 1.) Some of the ordinary appurtenances to the boiler are omitted when reference thereto is not necessary for the exemplification of the present invention.

75 The baffle system which assists in the effectiveness of the foregoing devices consists in the division of the chamber and the direction of the furnace gases by means of two, three or more baffles so constituted that the 80 gases from the furnace are carried across the vertical tubes at right angles thereto. This may be effected by the means illustrated in Fig. 9. The two spreader plates 32, 33, having holes to fit around the tubes 85 are clamped together by bolts 34. These plates support suitable corresponding fire brick strips 35 thus forming the equivalent of one baffle 36 and another baffle 37. This arrangement in conjunction with the shape 90 of the furnace and the flue space provided at each side 38 and 39 enable the superheater 26 to be very advantageously placed in the position shown where it receives the heat from the furnace gases after the temperature 95 has been lowered to a suitable degree. The path of the gases is shown by the arrows, being from left to right between and around the tubes past the superheater back from right to left between and around the 100 tubes then up to the top space which is specially adapted by this construction and arrangement for the economical employment of the economizer.

105 In Fig. 4 is represented a modification or alternative in which the water steam drum 15 is longitudinal with the headers. In this case the uptake is on one side of the boiler and the connections of parts are adjusted accordingly. Otherwise the construction is 110 the same as hereinbefore described.

Fig. 5 shows bottom header 10 vertical tubes 13, and one method of joining the element to the mud drum 14 consisting in flange 40 which may be screwed as shown 115 or may be welded to the header. 16 is the down comer expanded at 41 into the mud drum. 27 are hand holes and 28 doors for inspecting and cleaning.

In Fig. 6 is shown the front end of a 120 header with hand hole and door 30 instead of screw cap. The flanges 40 shown in Fig. 5 are secured to the mud drum as shown in Fig. 8. The flange of the upper header is secured to the saddle plate 9 in a similar 125 manner.

In Fig. 7 is shown an alternative method of securing the header to the mud drum by means of expanding. 10 is the header, 14 the mud drum, 43 the nipple which is ex- 130

panded into the header at one end, and into the mud drum at the other. When this method of connecting the elements is used the top header is connected to the steam 5 water drum in a like manner.

I claim—

A water tube boiler, comprising an inner and outer lining, a combustion chamber in the lower portion of the inner lining, a plurality of heating elements each consisting of a plurality of vertical tubes and upper and lower headers with which the tubes are connected, the elements being arranged with their tubes in staggered relation and their 10 headers on the same level and close together, the lower headers being arranged directly 15

above the combustion chamber, horizontal baffle plates projecting from opposite sides of the inner lining and through which the tubes pass, a steam drum, a mud drum, and 20 a plurality of down-comers connecting the steam and mud drums, the steam and mud drums and down-comers being outside of the inner lining.

Signed at Melbourne, in the State of Victoria, Australia, by me, the said HENRY ALEXANDER TURNBULL this 25th day of May, 25 A. D. 1915.

HENRY ALEXANDER TURNBULL.

In the presence of—

CHARLES NICHOLAS COLLISON,
AMY MABEL VOIGS.
